US0D1069286S

(12) **United States Design Patent** (10) **Patent No.:** **US D1,069,286 S**
(45) **Date of Patent:** **** Apr. 1, 2025**

(54) **TOP MAT FOR WASHER AND DRYER**

(71) Applicant: **Dongguan Linaidou Trading Co., Ltd.**, Dongguan (CN)

(72) Inventor: **Ruiqing Guan**, Huizhou (CN)

(73) Assignee: **Dongguan Linaidou Trading Co., Ltd.**, Dongguan (CN)

(**) Term: **15 Years**

(21) Appl. No.: **29/950,003**

(22) Filed: **Jun. 28, 2024**

(51) LOC (15) Cl. **15-05**

(52) U.S. Cl.

USPC **D32/25**; D32/57; D6/582

(58) **Field of Classification Search**

USPC D32/1, 5-6, 8, 10, 25, 55-57; D3/304; D5/53, 61; D6/406.6, 582-583; D7/550.1, 554.3; D15/89; D24/227

CPC A47L 23/266; B32B 2307/744; B32B 2471/04

(57) **CLAIM**

The ornamental design for a top mat for washer and dryer, as shown and described.

DESCRIPTION

FIG. 1 is a front perspective view of a top mat for washer and dryer, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 1.

The dash-dot-dash broken lines define the boundary of an enlarged view and form no part of the claimed design.

1 Claim, 9 Drawing Sheets
